-76-

The diagram illustrates a track section with a switch and a turnout. The main track is represented by a horizontal line with vertical cross-ties. A switch is located on the left, indicated by a curved arrow pointing to the right. A turnout is on the right, indicated by a curved arrow pointing to the left. The turnout is labeled with the number '72'.

UNITED STATES PATENT OFFICE.

PABLO PARIS, OF NEW YORK, N. Y.

TYPE-SETTING MACHINE.

1,259,900.

Specification of Letters Patent.

Patented Mar. 19, 1918.

Application filed February 14, 1917. Serial No. 148,481.

To all whom it may concern:

Be it known that I, PABLO PARIS, a citizen of the Republic of Venezuela, and resident of New York city, in the county of 5 New York and State of New York, have invented certain new and useful Improvements in Type-Setting Machines, of which the following is a specification.

This invention relates to apparatus where- 10 by the operation of a key board having letter and number keys, automatically produces the selection of printing type from a suitable magazine, and causes such type to be placed or set up in a chase in the proper sequence 15 and position; whereby the chase or form is adapted to be placed in a suitable press to take an impression from the matter set up, and produce the desired printing.

The object of the present invention is to 20 provide an improved mechanism for producing these results, wherein the act of depressing any one of the keys will first select the corresponding type and cause it to be deposited in a guideway, and thereupon such type 25 will be advanced and placed in the chase.

Another object of the invention is to provide an improved means for very quickly advancing the selected type to the chase, that is actuated solely by the depression of 30 the key.

Another object is to provide improved 35 mechanism for advancing the chase to consecutive positions relative to the guide-way along which the type are advanced, for producing the several lines of printing.

In the accompanying drawings illustrating embodiments of my invention, Figure 1 is a plan view of the apparatus, partly in section. Fig. 2 is a vertical section on the 40 line 2—2 of Fig. 1. Fig. 3 is a transverse section on the line 3—3 of Fig. 1. Fig. 4 is a horizontal section on the line 4—4 of Fig. 2. Fig. 5 is a partial vertical section enlarged on the line 3—3 of Fig. 1. Fig. 6 is a fragmentary perspective view enlarged 45 of the bars connecting the key levers with the selectors. Figs. 7, 8, 9, and 10 show details of the same. Fig. 11 is a detail view enlarged of the lower portion of the carriage. Fig. 12 is a section on the line 12—12 of Fig. 11. Fig. 13 is a side elevation, and Fig. 14 is a vertical section of the actuating 50 means for the type in the holders. Figs. 15 and 16 show the carrier.

As shown in the drawings, the apparatus 55 comprises essentially a magazine composed of a series of type holders, each containing a considerable number of the same type; a keyboard with connections for causing the act of depressing a key to effect the selection and delivery of the corresponding type into a suitable guide-way; also a carriage and chase arranged to reciprocate and advance across the end of the guide-way to receive the selected type as fed along the 65 guide-way by suitable advancing means, controlled or actuated by the depression of the key. The apparatus further includes means for automatically advancing the carriage 70 step-by-step after each type is advanced for spacing if desired; and also means for the line-spacing movement of the chase.

At the upper part of the apparatus, I provide a magazine in the form of a double series of type holders, indicated by 1 and 2, 75 that are composed of channels 3 in a frame 48, carrying a set of type 4 in each channel as shown in detail in Fig. 5. The type channels in the two sets are arranged opposite guide-ways 5 and 6, see Fig. 1. In each channel is arranged a follower 7, connected to a band 8 (see Figs. 13 and 14) passing around a drum 9, controlled by a spiral spring 15, and a ratchet 10 and pawl 11. By this means when the drum is released from 80 the pawl the type will be forced to the inner end of the channel and pass into the guide-way 5 or 6. Each of the type channels or holders 3 is provided with similar actuating means for the type as just set 85 forth. At the end of each type channel a slide 12 reciprocates vertically to have its beveled upper end move across the end of the type channel 3 adjacent the guide-way 5 or 6. This slide 12 is pivoted on the end 90 of a rock bar 13 (see Fig. 5) and is normally drawn up by spring 14 to extend into the channel and prevent the type therein being forced by the band 8 into the guide-way. The drum 9 is rotated by the spring 15 to 100 wind up the band and advance the type. The pawl 11 connects with the rock bar 13 by a link 16, whereby the pawl is normally held above the ratchet wheel 10, as shown at the left in Fig. 5, permitting the spring 105 to act to draw the type toward the guide-way, and the end type will be pressed against the slide 12 to prevent its escape.

It will be observed that this pawl 11 lies just beyond the end of a tooth, and when the slide 12 is drawn downwardly, as indicated at the right in this view, the pawl will engage the tooth of the ratchet wheel and permit turning of the ratchet wheel by the spring for nearly the distance of one tooth. This will serve to advance the end type into the guide-way 5, the pawl preventing further advance of the follower and type. The return of the slide 12 by its spring on release of bar 13 will cause the sharp end of the slide to pass across the end of the next succeeding type and engage its outer face, which is done before the pawl is again elevated sufficiently to release the ratchet wheel, thus preventing advance of the end type until the slide is again retracted. The slide is pressed against a guide 17 by spring 18.

At the front of the machine is a key board denoted generally by 19, comprising a series of key bars 20 extending rearwardly and suitably pivoted at their rear ends at 21, see Fig. 2. Each key bar has means connecting it with one of the said selector bars 13, see Fig. 6. Beneath each key bar 20, is arranged a bar 22 parallel therewith and which is suitably supported for parallel downward movement when depressed by a lug 23 on the key bar engaging the bar 22. The bar 22 is supported by arms 24 and 25 of a pair of angle levers, whose upper arms 26 and 27 are connected by a link 28. The purpose of this is to cause parallel movement of the bar 22 upon engagement thereof by the superposed key bar 20. It is to be understood that for each of the key bars 20 there is a bar 22 supported by angle levers, arranged to produce the desired parallel movement on depression of the key lever. 40

Beneath the said bars 22 are arranged a set of transverse bars 29, each having a lug 30 projecting upwardly in position for engagement with one of the bars 22. For convenience of arrangement and operation, the lugs 30 are arranged diagonally across the machine. The bars 29 are each supported by the arms 31 and 32 of bent levers 50 whose arms 33 and 34 are connected by a link 35; whereby to produce parallel movement of the transverse bar 29. Each bar 29 has a connector 36 secured thereto, projecting upward adjacent one of the said rock bars 13 that controls the selector slide 12, as shown in Fig. 5. It will be seen from Fig. 6 that the connector has a cross-head 37, one arm of which will engage the bar 13 to draw it and the slide downwardly on depression of a key lever, through the described bar 22 and transverse bar 29. But by shifting the upper portion of this connector 36, the opposite arm of the cross-head will be brought above the adjacent rock bar 13^x.

65 The type holders are divided into two sets,

there being one connector 36 for each pair of type holders and connected rock bars 13, such as 13 and 13^x in Fig. 6. The object of this is to arrange the capital letter type in one set and lower case type in the second set. For instance, the rock bar 13 being actuated by the connector 36 will serve to select a lower case letter, while if the connector is shifted to actuate the rock bar 13^x instead of the bar 13, then the capital for the same letter will be selected. In other words shifting the selector 36 changes from capitals to small letters and vice versa.

All of the connectors 36 pass through a shifting member in the form of a slotted frame plate 38, see Figs. 3 and 5.

To shift this plate 38 a key 39 is provided, see Fig. 2. This key connects by lever 40 and link 41 with a bent lever 42, the latter being secured to the lower member 43 of the frame 38. The key 39 may be locked in depressed position by a spring arm 44. This will serve to shift all of the connectors 36 to the rear, as indicated in Fig. 2, and they will engage with the rock bars 13^x instead of the rock bars 13, by the cross-heads 37.

The plate 38 and its lower portion 43 form a kind of frame that is shiftable back and forth and rests on ball bearings as shown at 45 in Fig. 2. This frame will be reciprocated by the key 39 and carry the connectors to engage either set of selector slides. This frame carries all of the said angle bars supporting the bars 22 and bars 29. Stops 137, 237 limit the back and forth movement of frame 38.

It will be observed from Fig. 1 that there are two sets of type holders 1 and 2 that serve to advance the type into the guide-ways 5 and 6 respectively. Half of the keys and key bars on one side coöperate with one set and the remaining ones with the opposite set.

At the rear of the guide-ways 5 and 6 they converge, and the type by the advancing means from each of the guide-ways, is passed through an outlet channel at 46.

An advancing means is provided for each of these guideways, that are in duplicate, one of them connected with each half of the bank of keys. This device is in the form of an extensible and contractible device such as a lazy-tong mechanism shown in Figs. 1 and 2. On a bracket 47 supporting the frame 48 containing the guide-way 5, is a bar 49 having links 50 and 51 at its upper and lower ends respectively. These links 50 and 51 are connected by links 52 and 53 respectively, with levers 54 and 55 mounted on a fixed pivot 56. The latter levers connect with a series of linked levers 57 and 58 shown extended in broken line position, and shown in the normal position in full lines. The forward links 59 and 60 connected with the levers 57 and 58 are pivoted to a carrier 130

72 that slides in the guide-way 5. This carrier is advanced from its normal position to the rear of all of the type channels to a forward position in which it will advance a selected type beyond the outlet channel 46 and into a chase located at this position. To swing the toggle links 50 and 51 I provide a pair of rack bars 61 and 62 pivoted to the rear ends of these links respectively. These 10 rack bars engage a gear 63 on opposite sides thereof, and are retained in engagement with such gear by arms 64 and 65. They engage the rear of the rack bars, preferably by rollers 66. These arms are free to swing on the 15 axis of the gear and it will be understood that rotation of this gear causes advance of the rack bars in opposite directions, so that one link is moved upwardly as the other one is drawn downwardly, thus serving to actuate 20 the lazy-tong levers 57 and 58. Adjacent the gear 63 is another gear 67 secured thereto, that is engaged by a segment arm 68 fast on a shaft 69 that swings on the bracket 47. The gear 63 is fast to a shaft 25 691 that carries a similar gear 711 meshing with a segment arm 71. The latter is fast on shaft 69 of the segment 68. A link 73 depends from segment 68 and a similar link 70 from segment 71. These links 73 and 70 30 carry a cross-bar 74 extending under the key bars at the right hand side of the machine. When any of these key bars is depressed this cross-bar 74 will move downward and thus swing the segment arms. This will turn the 35 gears and shift the rack bars, to actuate the lazy-tong device and advance the carrier 72 throughout the guide-way 5, to feed any selected type passed into the guide-way by the said selecting and advancing means, and 40 place such type in the chase. But the cross-bar 74 is placed a short distance below the key bars, so that the carrier will not be actuated until the described selecting means has caused the selected type to be advanced 45 into the guide-way.

For the other guide-way an identical form of lazy-tong mechanism is provided as indicated at 75 in Fig. 1. This mechanism is provided with a cross bar 76 similar to the 50 cross-bar 74 that extends across beneath all of the other key bars 20 that do not engage with the cross-bar 74. The latter set of key bars and the lazy-tong device with its carrier, coöperate with the set 2 of the type 55 holders on the right side of the machine.

It will thus be seen that to supply the type in the channels or holders, corresponding with the keys by which they are controlled, it is only necessary to depress the desired 60 keys, when the corresponding type will be released to be advanced into the guide by its controlling spring, which is done at once on the depression of the key. This depression of the key also serves to actuate the 65 lazy-tong device, that is advanced imme-

diatey after the selected type has been moved into the guide-way, and the carrier will cause such type to be advanced to the end of the guide-way. Suitable springs are provided for returning all of these parts to 70 normal positions. Each of the links 35 is connected by spring 77 with a fixed portion of the machine, that will return the bars 29 to normal positions when released. Each of the angle bars 24-26 is connected to a 75 retractile spring 78 (see Fig. 2) that will return the bars 22, and also the key bars 20 to normal position when released. Also a spring 79 serves to return the lazy-tong device to normal position. 80

To receive the type selected and advanced, I provide a carriage denoted generally by 80, that is movable laterally across the rear of the machine, which carriage is provided with a chase 148 arranged to slide in a frame 85 81 on the carriage, that has vertical movement on the carriage for the purpose of line spacing. The carriage is shown as supported at 82 and 83 on suitable bearings, and is drawn from right to left across the machine 90 by a band 84, carried by drum 85, that may contain the usual spring such as used in typewriters. The movement of the carriage in this direction is controlled by any suitable escapement device, indicated at 86 in 95 Fig. 2, that will permit the carriage to advance a unit distance at each operation of a key lever. On the escapement is an arm 87 connected with duplicate levers 88, which at the front have links 89 connecting with links 100 70, 73 whereby every depression of a key lever will operate the escapement. To return the carriage, I provide a draft rod 90 (see Fig. 1) that swings an arm 91 on a spindle 92 at the rear. On this spindle is a segment 105 arm 93 engaging a gear 94 fast on an escapement drum 95, around which one end of the band 84 is wound and secured. This band is not directly connected with the carriage, but through a lever 96 pivoted on the 110 carriage, the connected end of the lever having its stud 97 that secures it to the band working in a slot 98 in the carriage (see Figs. 1, 2 and 11). When the carriage is returned by the said operating means, the 115 lever 96 will first be swung to move stud 97 through the slot 98, and then the carriage is actuated. This lever is connected with the feeding means for the chase. 120

Adjustable stops are provided for the carriage that can be actuated from the front of the machine. As shown I provide a stop 99 that is threaded to move on a threaded rod 100, and plain rod 200, see Figs. 1 and 2. This rod 100 has a gear 101 meshing with 125 a gear 102 on a side shaft 103. The latter extends to the front of the machine, to be turned by a handle 104. An indicator guide 105 slides on a threaded shaft 106 to move a pointer 107 along a scale 108. This shaft 130

106 has a gear 109 meshing with a gear 110 on the shaft 103. A similar mechanism is provided on the opposite side of the machine for operating a stop identical with the 5 stop 99, controlled by handle 111 through a side shaft 112.

A separate space key 113 is provided at the front, that rocks a lever 114 to swing link 115, connecting with the escapement 10 arm 87.

The chase frame 81 is provided with racks 116 and 117 on its rear face that engage worms 118 and 119 mounted on vertical shafts 120 and 121 respectively, as 15 shown in Figs. 1, 2, and 3. These shafts rotate in unison by having miter gears 122 and 123 that engage miter gears 124 and 125 fast on a cross-shaft 126. The latter shaft has a gear 127 at one side meshing 20 with a large gear 128, provided with a handle 129. The latter serves to rotate the worm wheels and elevate or depress the chase as may be desired. The said shaft 126 is supported by uprights 130 and 131 25 on the carriage 80. At the lower ends of the shafts 120 and 121 are arranged gears 132 and 133 each provided with pawls 134 that mesh with ratchet wheels 135, 136 that are fast on these two shafts. Said gears, 30 132, 133, mesh with racks 138 and 139 on a slide 140 on the carriage. This slide is pivoted to the lever 96 whereby it connects with the band 84. It has been set forth that when the carriage is returned, this lever 35 will first be swung before the carriage moves. Hence slide 140 will be shifted to turn the ratchet wheel, and through the pawls the two worm shafts will be swung, which is sufficient to advance the chase the proper distance for line spacing. The pawls and ratchets will permit the reverse movement of the worm shafts to elevate the chase when desired. In order to permit the chase 40 to be depressed without moving the slide 140, means are provided to shift the pawls. A head 141 (Fig. 2) is slidable on each shaft 120, 121 and has its lower end conical to engage pins 142 on the several pawls, serving to shift the pawls away from the 45 ratchet wheels.

For the purpose of freeing the carriage from the escapement I provide a key 143 that connects with a lever 144 by link 145 (Fig. 4), and through link 146 serves to 55 shift the escapement 86 out of range of the carriage rack 147.

Having thus described my invention, what I claim is:

1. In a type setting machine, the combination of a guideway for the type, a carrier 60 slidable in the guide-way to advance the type, a set of keys, and a lazy-tong device connected with the carrier and arranged to be reciprocated by any of the 65 keys whereby the carrier is advanced on

operation of the key to convey the type through the guide-way, and the carrier returned to normal position.

2. In a type setting machine, the combination of a guide-way for the type, a series 70 of type holders arranged to deliver their type into the guide-way, a carrier slidable in the guide-way to advance the type as delivered from the holders, a set of keys corresponding with the respective type holders, 75 connections between each key and its type holder including means whereby on operation of a key a single type will be advanced from the holder to the guide-way, and a lazy-tong device connected with the carrier and arranged to be reciprocated by any of the keys whereby the carrier is advanced on operation of the key and subsequent to the delivery of a type to the guide-way to convey the selected type through 80 the guide-way and the carrier then returned to normal position.

3. In a type setting machine, the combination of a guide-way for the type, a carrier 90 slidable in the guide-way to advance the type, a set of lazy-tong levers connected with the carrier at one end and having stationary pivots at the other end, a key lever, a gear swung by the key lever, and a pair of rack bars secured to the upper and lower 95 members respectively of the lazy-tong levers, said rack bars being retained in engagement with the opposite sides of said gear to be reciprocated in opposite directions thereby, whereby the reciprocation of the 100 key lever will open and close the lazy-tong lever to reciprocate the carrier.

4. In a type setting machine, the combination of a guide-way for the type, a carrier 105 slidable in the guide-way to advance the type, a set of lazy-tong levers connected with the carrier at one end and having stationary pivots at the other end, a key lever, a rack swung by the key lever, a pinion engaging said rack, a gear secured to said 110 pinion, and a pair of rack bars secured to the upper and lower members respectively of the lazy-tong levers, said rack bars being retained in engagement with the opposite sides of said gear to be reciprocated in 115 opposite directions thereby, whereby the reciprocation of the key levers will open and close the lazy-tong levers to reciprocate the carrier.

5. In a type setting machine, the combination of a guide-way for the type, a series 120 of type-holders arranged to deliver their type into the guide-way, a carrier slidable in the guide-way to advance the type as delivered from the holders, a set of keys corresponding with the respective type-holders, 125 connections between each key and its type holder including means whereby on operation of a key a single type will be advanced from the holder to the guide-way, and a 130

5 lazy-tong device connected with the carrier arranged to be reciprocated by the operation of any of the keys whereby the carrier is advanced on depression of the key to convey the type through the guide-way and then returned to normal position.

6. In a type setting machine, the combination with a set of type holders, of a guide-way for the type adjacent the holders to receive the type, a carrier slideable in the guide-way to advance the type, a set of lazy-tong levers connected with the carrier at one end and having stationary pivots at the other end, a key lever, a gear swung by the key lever, a pair of rack bars pivoted to the upper and lower end 10 members respectively of the lazy-tong levers and arranged to engage opposite sides of said gear, and a pair of arms pivoted to swing on the axis of said gear and each provided with guiding means for the rack 15 bars respectively to retain the rack bars meshing with the gear while reciprocated by the gear, whereby the operation of the key lever will reciprocate the rack bars in opposite directions to open and close the 20 lazy-tong levers and reciprocate the carrier. 25

7. In a type setting machine, the combination with a set of type holders, of a guide-way for the type adjacent the holders to receive the type, a carrier slideable in the 30 guide-way to advance the type, a set of key bars each arranged to control the reciprocation of the carrier to advance a type fed to the guide-way, a set of bars adjacent each key lever to be depressed thereby and 35 mounted for parallel movement, a set of transverse bars each connected to be swung by one of said latter bars when depressed and mounted for parallel movement, a selector slide for each of the type holders, 40 and a connector between the selector slides and the said transverse bars whereby the depression of each key lever will control the selection of a type from the holder and also through the carrier serve to advance the 45 selected type.

8. In a type setting machine, the combination with a set of type holders, of a guide-way for the type adjacent the holders to receive the type, a carrier slideable in the 50 guide-way to advance the type, a set of key bars each arranged to control the reciprocation of the carrier to advance a type fed to the guide-way, a set of bars adjacent each key lever to be depressed thereby and 55 mounted for parallel movement, a set of transverse bars each connected to be swung by one of said latter bars when depressed and mounted for parallel movement, a selector slide for each of the type holders, 60 and a connector between the selector slides and the said transverse bars whereby the depression of each key lever will control the selection of a type from the holder and also through the carrier serve to advance the 65 selected type, said type holders being ar-

ranged in pairs, said connector for the type selectors being shiftable to control at will either one of a pair of type holder selectors, and means for shifting all of the said connectors. 70

9. In a type setting machine, the combination with a set of type holders, of a guide-way for the type adjacent the holders to receive the type, a carrier slideable in the guide-way to advance the type, a set of key bars each arranged to control the reciprocation of the carrier to advance a type fed to the guide-way, a set of bars adjacent each key lever to be depressed thereby and mounted for parallel movement, a set of 75 transverse bars each connected to be swung by one of said latter bars when depressed and mounted for parallel movement, a selector slide for each of the type holders, a connector between the selector slides and the 80 said transverse bars whereby the depression of each key lever will control the selection of a type from the holder and also through the carrier serve to advance the selected type, a spring for each type holder tensioned to advance the type to the carrier, a ratchet wheel connected with the spring, and a pawl escapement for the ratchet wheel, said slide serving to normally retain the first type in the holder against advancement by the spring and being retracted from the key depression to permit the said type to advance to the guide-way, said pawl and ratchet serving to permit advance of the type a unit distance only in such operation, said pawl being released for said control when said slide is withdrawn for advancement of the type and being moved away from the ratchet on return of the slide to engage and retain the next successive 90 type in the type holder. 95

10. In a type setting machine, the combination with a set of type holders, a ratchet wheel, a spring on the ratchet wheel arranged to advance the type in the holder, a 100 pawl escapement for controlling the ratchet wheel and spring, a key bar, and a slide reciprocated by the key bar to engage the type at the end of the holder that is pressed against the slide by the spring, said slide 105 normally retaining the type from being advanced, said pawl having connection with the slide to normally hold the pawl free of the ratchet wheel, but cause the pawl to engage the ratchet wheel when withdrawn to 110 permit advancement of the type, the pawl thereby permitting advance of the ratchet wheel and type a unit distance only, said slide on return of retraction of the key serving to engage the next type and retain 115 it in position on release of the ratchet wheel by the pawl. 120

11. The combination of a type holder, means to advance the type in the holder, and a slide arranged to engage the end type 130

in the holder, said advancing means being controlled by the slide to advance the type a unit distance when the slide is withdrawn, the slide serving to engage the next successive type when retracted to normal retaining position.

12. In a type setting machine, the combination of a set of pivoted key levers, a bar arranged beneath each of said levers, a pair 10 or bent levers for each of said bars by which each bar is supported, a rod connecting each pair of bent levers for one bar whereby the bars are given a parallel movement from the levers, a set of type holders one for each key 15 lever, a set of selectors between each key lever and the type holder, a set of transverse bars one connected for operation with each of said parallel bars, and a connector between each transverse bar and one of said 20 selectors.

13. In a type setting machine, a combination of a set of pivoted key levers, a set of bars one for each lever connected therewith, a set of transverse bars one for each of said 25 bars and extending transverse thereto to be operated thereby, a pair of bent levers for each transverse bar by which it is supported for movement, a bar connecting each of said pair of bent levers whereby each transverse 30 bar is given a parallel movement, a set of type holders, a set of selectors for the type holders, and a connector between each selector and one of said transverse bars.

14. In a type setting machine, the combination of a guide-way for the type, a carrier 35 slidable in the guide-way to advance the type, a set of lazy-tong levers connected with the carrier at one end and having stationary pivots at the other end, a set of 40 key levers, a rack swung by the key lever, a pinion engaging said rack, a gear secured to said pinion, a pair of rack bars secured to the upper and lower members respectively 45 of the lazy-tong levers, said rack bars being retained in engagement with the opposite sides of said gear to be reciprocated in opposite directions thereby, whereby the reciprocation of the key lever will open and close the lazy-tong levers to reciprocate the carrier, a shaft on which said rack is secured, 50 an arm on said shaft, and a bar secured between said arm and said rack and extending beneath the key levers whereby depression of any key lever will engage said bar and swing said rack to actuate the lazy-tong levers.

15. In a type setting machine, the combination with means for selecting and advancing type along a guide-way, of a carriage supported for horizontal movement transverse to the guide-way, a chase mounted on 60 said carriage, means for automatically causing advance of the carriage by the type selecting and feeding means at each operation, and a worm wheel controlling means for the

chase arranged to vertically shift the chase on the carriage automatically at the end of each traverse of the carriage.

16. In a type setting machine, the combination with means for selecting and advancing type along a guide-way, of a carriage supported for horizontal movement transverse to the guide-way, a chase mounted on said carriage, means for automatically causing advance of the carriage by the type selecting and feeding means at each operation, and a worm wheel controlling means for the chase arranged to vertically shift the chase on the carriage automatically at the end of each traverse of the carriage, and hand-operated means for actuating said worm wheel device to shift the chase at will. 75

17. In a type setting machine, the combination with means for selecting and advancing type along a guide-way, of a carriage supported for horizontal movement transverse to the guide-way, a chase frame mounted on the carriage for vertical movement, racks on the chase frame, a pair of vertical shafts on the carriage mounted to rotate, a worm on each shaft that engages one of said racks whereby to traverse the chase frame by said shafts, a gear connected with each said shaft, a slide on the carriage having rack portions engaging said gears to rotate the shafts and shift the chase frame, a lever on the carriage connecting with said slide, and a member arranged to move the carriage and connected with said lever by a stud, the carriage frame having a slot arranged to engage said stud at opposite portions whereby shifting of said member will first swing said lever to advance the chase frame until the stud swings in said slot whereupon the carriage will be moved. 80

100

18. In a type setting machine, the combination with means for selecting and advancing type along a guide-way, of a carriage supported for horizontal movement transverse to the guide-way, a chase frame mounted on the carriage for vertical movement, racks on the chase frame, a pair of vertical shafts on the carriage mounted to rotate, a worm on each shaft that engages one of said racks whereby to traverse the chase frame by said shafts, a gear connected with each said shaft, a slide on the carriage having rack portions engaging said gears to rotate the shafts and shift the chase frame, a lever on the carriage connecting with said slide, and a member arranged to move the carriage and connected with said lever by a stud, the carriage frame having a slot arranged to engage said stud at opposite portions whereby shifting of said member will first swing said lever to advance the chase frame until the stud swings in said slot whereupon the carriage will be moved, said gears on the worm shafts having a pawl and ratchet connection with the shafts to permit 110

- return of the chase frame when advanced by reverse rotation of the shafts.
19. In a type setting machine, the combination with means for selecting and advancing type along a guide-way, of a carriage supported for horizontal movement transverse to the guide-way, a chase frame mounted on the carriage for vertical movement, racks on the chase frame, a pair of vertical shafts on the carriage mounted to rotate, a worm on each shaft that engages one of said racks whereby to traverse the chase frame by said shafts, a gear connected with each said shaft, a slide on the carriage having rack portions engaging said gears to rotate the shafts and shift the chase frame, a lever on the carriage connecting with said slide, a member arranged to move the carriage and connected with said lever by a stud, the carriage frame having a slot arranged to engage said stud at opposite portions whereby shifting of said member will first swing said lever to advance the chase frame until the stud swings in said slot whereupon the carriage will be moved, said gears on the worm shafts having a pawl and ratchet connection with the shafts to permit return of the chase frame when advanced by reverse rotation of the shafts, means for freeing said ratchets of their pawls for independent movement of the shafts, a cross-shaft arranged to rotate the two shafts in unison, and a handle for rotating said cross-shaft.
20. In a type setting machine, the combination of a guide-way for the type, a carrier slidable in the guide-way to advance the type, and a device connected with the carrier and arranged to be expanded and contracted by any of the keys, whereby said carrier is positively pushed forward by said device on operation of a key to advance the type through said guide-way and is thereafter positively retracted by the same to normal position.
21. In a type setting machine, the combination of a guide-way for the type, a carrier slidable in the guide-way to advance the type, an expansible and contractible device connected at one end with said carrier to positively push said carrier forward and thereafter positively retract the same, a gear connected to expand and contract said device, and a key lever connected to rotate said gear.
22. In a type setting machine, the combination of a guide-way for the type, a carrier slidable in the guide-way to advance the type, an extensible and contractible device connected at one end with said carrier to operate the same, a pair of toothed elements connected to operate said device, a gear disposed between said toothed elements and engaged thereby at opposite sides; and a key lever connected to rotate said gear.
23. In a type setting machine, the combination with a set of type holders; of a guide-way for the type adjacent the holders to receive the type; a carrier slidable in the guide-way to advance the type; a set of key bars each arranged to control the reciprocation of the carrier; a set of transverse bars one individual to each key bar disposed beneath said key bars so as to be engaged and depressed thereby; a selector slide for each type holder; and connections between said slides and said transverse bars, whereby the depression of each key bar will control the selection of a type from the holder and also through the carrier serve to advance the selected type.
24. In a type setting machine, the combination with a set of type holders; of a guide-way for the type adjacent the holders to receive the type; a carrier slidable in the guide-way to advance the type; a set of key bars each arranged to control the reciprocation of the carrier; a set of transverse bars one individual to each key bar disposed beneath said key bars so as to be engaged and depressed thereby; a selector slide for each type holder; said type holders and slides being arranged in pairs for upper and lower case; connections between said slides and said transverse bars, whereby the depression of each key bar will control the selection of a type from the holder; and controlling means for said connections to govern the selection of upper or lower case.
25. In a type setting machine, the combination with a set of type holders; of a guide-way for the type adjacent the holders to receive the type; a carrier slidable in the guide-way to advance the type; a set of key bars each arranged to control the reciprocation of the carrier; a set of transverse bars one individual to each key bar disposed beneath said key bars so as to be engaged and depressed thereby; a selector slide for each type holder; a selector bar for each slide, said type holders, slides and selector bars being arranged in pairs for upper and lower case; connections between said selector bars and transverse bars, whereby the depression of each key bar will control the selection of a type from the holder; and controlling means for said connections to govern the selection of upper and lower case.
26. In a type setting machine, the combination with a set of type holders; of a guide-way for the type adjacent the holders to receive the type; a carrier slidable in the guide-way to advance the type; a set of key bars each arranged to control the reciprocation of the carrier; a transverse bar individual to each key bar and connected to be depressed thereby; a selector slide for each type holder; a selector bar for each slide, said type holder, slides and selector bars being arranged in pairs for upper and lower case.

lower case; and a connector bar between each transverse bar and the corresponding pair of selector bars, whereby the depression of each key will control the selection of a type from the holder, each connector bar being shiftable to selectively actuate the upper or the lower case selector bar.

27. In a type setting machine, the combination with a set of type holders; of a guide-way for the type adjacent the holders to receive the type; a carrier slidable in the guide-way to advance the type; a set of key bars each arranged to control the reciprocation of the carrier; a transverse bar individual to each key bar and connected to be depressed thereby; a selector slide for each type holder; a selector bar for each slide, said type holder, slides and selector bars being arranged in pairs for upper and lower case; a connector bar between each transverse bar and the corresponding pair of selector bars, whereby the depression of each key will control the selector of a type from the holders; each connector bar being shiftable to selectively actuate the upper or the lower case selector bar, and means for shifting all of said connector bars in unison.

28. In a type setting machine, the combination with a set of type holders, of a guide-way for the type adjacent the holders to receive the type; a carrier slidable in the guide-way to advance the type; a set of key bars each arranged to control the reciprocation of the carrier; a transverse bar individual to each key bar and connected to be depressed thereby; a selector slide for each type holder; a selector bar for each slide, said type holders, slides and selector bars being arranged in pairs for upper and lower case; a connector bar between each transverse bar and the corresponding pair of selector bars, whereby the depression of each key will control the selector of a type from the holders; each connector bar being shiftable to selectively actuate the upper or the lower case selector bar, a case key; and means actuated by said case key for shifting all of said connector bars.

29. In a type setting machine, the combination with a set of type holders; of a guide-way for the type adjacent the holders to receive the type; a carrier slidable in the guide-way to advance the type; a set of key bars each arranged to control the reciprocation of the carrier; a transverse bar individual to each key bar and connected to be depressed thereby; a selector slide for each type holder; a selector bar for each slide, said type holders, slides and selector bars being arranged in pairs for upper and lower case; and a headed connector bar between each transverse bar and the corresponding pair of selector bars, each connector bar being shiftable to engage the

head alternatively with the upper or the lower case selector bar.

30. In a type setting machine, the combination with a set of type holders, and a guide-way for the type adjacent said holders to receive the type therefrom; of a carrier slidable in the guide-way to advance the type; a set of key bars each arranged to control the movement of the carrier; a set of transverse bars one individual to each key bar disposed beneath said key bars so as to be engaged and depressed thereby; a selector slide for each type holder; connections between said slides and said transverse bars, whereby the depression of each key bar will control the selection of a type from the holder; and mechanism for controlling the selection of upper and lower case types upon the depression of said key bars.

31. In a type setting machine, the combination of a set of type holders; a ratchet wheel; a spring on said wheel arranged to advance the type in the holder; a pawl escapement for controlling the ratchet wheel and spring; an endwise movable vertical slide having its upper end normally engaging the type at the end of the holder that is pressed against the said slide end by said spring; a key bar; and connections between said key bar and said slide and escapement for moving the slide downward to release the type and for operating the escapement.

32. In a type setting machine, the combination of a set of type channels and a guide-way into which they open; of a spring controlled device for each channel to advance the type therein toward said guide-way; a controller for each advancing device; a set of endwise movable vertical slides, one for each channel, having their upper ends normally engaging the type at the ends of said channels that are pressed thereagainst by said advancing devices; and a set of key bars for moving said slides downward to disengage the type.

33. In a type setting machine, the combination with means for selecting and advancing type along a guide-way; of a carriage supported for movement transverse to the guide-way; a chase mounted on said carriage; means for automatically causing advance of the carriage by the type selecting and advancing means at each operation; means for line-spacing the chase, embodying a rack on the chase frame, and a worm shaft engaging said rack; means for returning the carriage; and means operated automatically by the carriage returning means for rotating said worm shaft.

34. In a type-setting machine, the combination with a carriage, a chase mounted thereon, and means for feeding selected type to the chase and for letter-spacing the car-

riage; of means for line-spacing said chase; means including a draw belt connected to the carriage for returning the latter from the end of one line to the beginning of the next line; and means operated automatically by the movement of said belt for actuating said line-spacing means.

35. In a type-setting machine, the combination with a carriage, a chase mounted thereon, and means for feeding selected type to the chase and for letter-spacing the carriage; of means for line-spacing said chase; a draw belt connected to the carriage; a push rod connected to move said belt in one direction, so as to return the carriage to position to begin a new line; and means operated automatically by the movement of the belt for actuating said line-spacing means.

36. In a type-setting machine, the combination with a carriage, a chase mounted thereon, and means for feeding selected type to the chase and for letter-spacing the carriage; of means for line-spacing said chase; a draw belt connected to the carriage; a pull rod connected to move said belt in one direction, so as to return the carriage to position to begin a new line; and a lever on said carriage operated by the movement of the belt and connected to actuate said line-spacing means.

37. In a type-setting machine, the combination with a carriage, a chase mounted thereon, and means for feeding selected type to the chase and for letter-spacing the carriage; of means for line-spacing said chase; means including a draw belt connected to the carriage for returning the latter to position to begin a new line; and a lever on said carriage operated by the movement of the belt and connected to actuate said line-spacing means.

38. In a type-setting machine, the combination, with a carriage, a chase mounted thereon, and means for feeding selected type to the chase and for letter-spacing the carriage; of means for line-spacing the chase, embodying a rack on the chase frame, and a worm shaft engaging said rack; means for returning the carriage to position to begin a new line; and means operated automatically by the carriage-returning means for rotating said worm shaft.

39. In a type-setting machine, the combination, with a carriage, a chase mounted thereon, and means for feeding selected type to the chase and for letter-spacing the carriage; of means for line-spacing the chase,

embodying a rack on the chase frame, and a worm shaft engaging said rack; means including a draw belt connected to the carriage for returning the latter to position to begin a new line; and means operated automatically by the movement of said belt for rotating said worm shaft.

40. In a type-setting machine, the combination, with a carriage, a chase mounted thereon, and means for feeding selected type to the chase and for letter-spacing the carriage; of means for line-spacing the chase; means for returning the carriage to position to begin a new line; a slide on said carriage positively shifted when said carriage-returning means is actuated; and means operated positively by said slide for positively driving said line-spacing means.

41. In a type setting machine, the combination, with a carriage, a chase mounted thereon, and means for feeding selected type to the chase and for letter-spacing the carriage; of means for line-spacing the chase; means for returning the carriage to position to begin a new line; a member carried by said carriage and movable relatively to the same, said member actuated automatically and positively by said carriage-returning means; and means operated automatically and positively by the movement of said member for positively driving said line-spacing means.

42. In a type-setting machine, the combination, with a carriage, a chase mounted thereon, and means for feeding selected type to the chase and for letter-spacing the carriage; of means including a draw belt connected to the carriage for returning the latter to position to begin a new line; a slide on said carriage connected to be operated by the movement of said belt; and means actuated by said slide for positively driving said line-spacing means.

43. In a type-setting machine, the combination, with a carriage, a chase mounted thereon, and means for feeding selected type to the chase and for letter-spacing the carriage; of means for positively shifting said chase vertically from line to line, to line-space it; means for positively returning said carriage from the end of one line to the beginning of the next line; and means operated directly and positively by said carriage-returning means for directly and positively driving said line-spacing means.

PABLO PARIS.
